UNITED STATES PATENT OFFICE.

JAMES WILKINSON, OF BOSTON, MASSACHUSETTS, ASSIGNOR TO GENERAL ELECTRIC COMPANY, A CORPORATION OF NEW YORK.

BOILER-FEED SYSTEM.

1,105,736.

Specification of Letters Patent.

Patented Aug. 4, 1914.

Application filed May 31, 1912. Serial No. 700,658.

To all whom it may concern:

Be it known that I, JAMES WILKINSON, a citizen of the United States, residing at Boston, county of Suffolk, State of Massachusetts, have invented certain new and useful Improvements in Boiler-Feed Systems, of which the following is a specification.

The present invention relates to boiler feed systems wherein a plurality of boilers 10 is arranged in a battery for supplying steam to turbines or other steam consuming apparatus.

At the present time great difficulty is experienced in getting boiler attendants to 15 properly operate their boilers so that each will perform its share of the total work. This is due chiefly to the fact that said attendants have no means of telling just what proportion of the total load their boilers 20 should carry.

My invention has for its object to overcome the objection above noted and to provide means which automatically indicate at 25 each boiler the proportion of the total amount of steam that it should deliver.

My invention also includes means for indicating to the attendant when his boiler is furnishing its share of the total load and also means for indicating at some suitable 30 point the work being performed by each boiler and its relation to the total work.

For a complete understanding of my invention attention is directed to the following specification wherein I have illustrated 35 certain forms which my invention may take.

In the accompanying drawings, Figure 1 is a diagrammatic representation of a battery of three boilers equipped with my invention; Fig. 2 is a diagram showing the electrical circuits in the installation shown in Fig. 1; Fig. 3 is a diagram of circuits showing telltale indicators at some distant point; Fig. 4 is a section of the header 40 showing the Pitot nozzles; and Fig. 5 is a side elevation of a modified form of master meter.

Each boiler 1 is connected by a riser 2 with a common header 3 which conveys the 45 steam to the turbines or other consumptive apparatus. At some point in said header between the last boiler and the engine is inserted a pressure difference responsive device, such as the Pitot nozzles 4, 5 connect-

ed by the pipes 6, 7 with the two legs of a 55 U-shaped tube 8 containing a body of mercury 9. One of the nozzles faces toward the direction of the flowing steam as indicated by the arrow, Fig. 1, and is called the leading nozzle while the other nozzle faces in 60 the opposite direction and is called the trailing nozzle. The pipes leading from the nozzles to the U-tube are marked L and T respectively to indicate their connection to the leading and trailing nozzles. The ac- 65 tion of the steam flowing through the header past the nozzles 4, 5 produces a pressure difference in the two legs of the tube 8 that bears a definite relation to the rate of flow of the steam so that the mercury will stand 70 at a higher level in the leg connected to the trailing nozzle.

At each boiler is located a similar auxiliary meter 10 with its Pitot tubes or nozzles 11 in the riser connecting said boiler 75 with the header, so that these meters will indicate the flow of steam supplied by their respective boilers. Adjacent to each boiler meter is a tier of visual indicators, preferably electric lamps 12. Any number may 80 be used, but I find that four is sufficient for ordinary installations. Each lamp has one terminal grounded and the other terminal connected to an insulated contact 13 projecting through the wall of the low pressure 85 leg of the master meter 8, so as to be submerged by the mercury column in that leg when it rises to the level of said contact. The several contacts are inserted at different levels in said tube corresponding with the 90 positions of their respective lamps at the boiler meters. The lamps at the several boilers are connected in multiple, as shown in Fig. 2. A battery 14 is connected to the mercury in the master meter, one of its 95 terminals being grounded.

In operation, the rise and fall of the mercury in the low pressure leg of the master meter will successively close and open the circuits of the lamps by its contact with 100 their contacts 13, so that the fireman at each boiler can see how the total flow of steam in the header 3 is fluctuating. By observing at the same time the level of the mercury in the auxiliary meter 10 of his 105 boiler, he can see whether that boiler is carrying its share of the total load. If the mercury in his meter is above or below the

topmost lamp that is alight, he will regulate his fire to bring the top of his mercury column level with said lamp.

Fig. 3 shows how a telltale can be arranged 5 on the bridge of a ship or at any other distant point in a power plant, by simply putting one or more additional lamps in the circuit of each indicator lamp. These additional lamps may be either at some station 10 15 or at the master meter, as at 16, or both at the master meter and the distant station, as shown. Moreover, another indicating circuit may run from each boiler meter to the distant station, so that the official at 15 said station can see not only the total flow of steam but ascertain at the same time the performance of each individual boiler. Such circuits are shown in Fig. 3, the tiers of lamps 17 at the bridge being connected in 20 multiple circuit contacts in the low pressure leg of said boiler meters. A battery 19 is in circuit with the mercury in said boiler meters. Adjacent each boiler meter I also provide a tier of lamps 18 connected in series 25 with the lamps 17. These lamps will indicate at the respective meters the position of the mercury in the legs of the U-tubes, and may be compared with lamps 12 in lieu of the meniscus of the mercury column as used 30 in Fig. 1.

Fig. 5 shows a modified form of master meter in which the electrical contacts are arranged at varying distances apart, increasing from bottom to top, to correspond with 35 the increasing deflection of the mercury with increasing flow of steam in the header. This construction enables the meter to indicate equal increments of flow.

In accordance with the provisions of the 40 patent statutes, I have described the principle of operation of my invention, together with the apparatus which I now consider to represent the best embodiment thereof; but, I desire to have it understood that the 45 apparatus shown is only illustrative, and that the invention can be carried out by other means.

What I claim as new and desire to secure by Letters Patent of the United States, is,— 50 1. The combination with a battery of boilers having a common header and connections whereby the boilers feed into said common header, of a master steam flow meter for said header, an auxiliary flow meter for each connection, and means for indicating at each auxiliary meter the variations of the master meter.

2. The combination with a battery of boil-

ers having a common header and connections whereby the boilers feed into said common header, of a master steam flow meter for said header, an auxiliary flow meter for each connection, and electrical means for indicating at each auxiliary meter the variations of the master meter. 60 65

3. The combination with a battery of boilers having a common header and connections whereby the boilers feed into said common header, of a master steam flow meter for said header, an auxiliary flow meter for each connection, a tier of electric lamps adjacent to each auxiliary meter, and means for lighting said lamps in succession as the flow of steam in the header increases and for extinguishing said lamps as said flow diminishes. 70 75

4. The combination with a battery of boilers having a common header and connections whereby the boilers feed into said common header, of a master steam flow meter for said header, an auxiliary flow meter for each connection, and electrical means for indicating at each auxiliary meter and also at a distant station the variations of the master meter. 80

5. The combination with a battery of boilers having a common header and connections whereby the boilers feed into said common header, of a master steam flow meter for said header, an auxiliary flow meter for each connection, a tier of electric lamps adjacent to each auxiliary meter, means for lighting said lamps in succession as the flow of steam in the header increases and for extinguishing said lamps as said flow diminishes, and a tier of telltale lamps in series with the aforesaid tier and located at a distant station for indicating thereat the variations of said auxiliary meters. 85 90 95

6. The combination with a battery of boilers having a common header and connections whereby the boilers feed into said common header, of a master steam flow meter for said header, an auxiliary flow meter for each connection, a tier of electric lamps adjacent to each auxiliary meter, means for lighting said lamps in succession as the flow of steam in the header increases and for extinguishing said lamps as said flow diminishes, and means at a distant station for indicating the variations of each auxiliary meter. 100 105

In witness whereof, I have hereunto set my hand this 25th day of May, 1912. 110

JAMES WILKINSON.
